UNITED STATES PATENT OFFICE.

JOHN F. ANCONA, OF ROCHESTER, NEW YORK.

SLITTING AND WINDING MACHINE.

1,371,770.

Specification of Letters Patent. Patented Mar. 15, 1921.

Application filed April 2, 1917. Serial No. 159,266.

To all whom it may concern:

Be it known that I, JOHN F. ANCONA, a citizen of the United States, residing at Rochester, in the county of Monroe and State of New York, have invented or discovered certain new and useful Improvements in Slitting and Winding Machines, of which the following is a specification, reference being had therein to the accompanying drawings.

This invention relates to a machine for cutting or slitting a web of paper or other fabric in such a manner as to produce a plurality of narrow strips or tapes, and for separately winding upon suitable cores the several strips or tapes so formed.

In Letters Patent No. 1,222,914, granted to me April 17, 1917, I have shown and described a machine for printing narrow, elongated strips or columns of reading matter upon a continuous web by means of rotary printing cylinders, said strips being of greater length than the length or circumference of the printing cylinders, and being produced in continuous form, that is to say, being free from joints such as would be occasioned by printing the strips in sections and joining them together. To this end in said machine the printing surfaces are arranged in helical form on the printing cylinders, so that as the web of paper is passed through the machine the columns of reading matter are printed diagonally thereon, that is to say, at a slight inclination to the length of the web.

My prior patent aforesaid also discloses, but does not claim, means for cutting the web so as to separate the several columns of reading matter impressed thereon by the printing mechanism into individual strips or tapes, and such cutting mechanism constitutes a portion of the invention claimed in the present case. This cutting or slitting mechanism comprises, in general, a pair of coöperating helical slitting knives which are rotated in unison, so that as the web is passed longitudinally between them said web is cut diagonally, or upon lines whose inclination to the length of said web corresponds to the inclination of the printed columns of reading matter.

Under certain circumstances, however, instead of cutting the web immediately after

the printing operation to form the several tapes, it is found preferable (in order to prevent "offsetting" when a strip printed on both sides is wound up before the ink has had time to dry) to wind the complete web upon a suitable reel or roller with a tympan sheet or cloth, said tympan sheet being interposed between the several convolutions of the web. The present invention has therefore for an object to provide a machine capable of unwinding such a combined roll of printed web and tympan material, of re-winding the tympan sheet, and of slitting or cutting the web in the desired manner to form the strips or tapes.

Another object of the invention is to provide means for trimming the ends of the tapes formed by the slitting mechanism, so as to remove surplus material therefrom and give said ends such form or shape as may be necessary to adapt them to the purposes for which they are to be used or to such further operations as are to be performed thereon.

A further object of the invention is to provide improved winding mechanism for separately winding the several strips or tapes, produced by the slitting mechanism, upon individual cores. In carrying out this portion of the invention provision is made for moving the winding devices transversely of the web, as the winding progresses, in order to compensate for the inclined position of said strips with respect to the web.

The foregoing and other more particular objects of the invention, together with means whereby the same may be carried into effect, will best be understood from the following description of one form or embodiment thereof illustrated in the accompanying drawings. It will be understood, however, that the particular construction and adaptation described and shown have been chosen for illustrative purposes merely, and that the invention, as defined by the claims hereunto appended, may be otherwise practised without departing from the spirit and scope thereof.

In said drawings:

Figure 1 is a side elevation of the complete machine.

Fig. 2 is a plan view thereof.

Fig. 3 is a plan view, on a considerably

reduced scale, of the paper web, illustrating the manner in which the several strips or tapes are cut therefrom.

Fig. 4 is an enlarged plan view of a single strip or tape, portions of the web from which said strip is severed being shown in broken lines.

Fig. 5 is an elevation, partly broken away, of the cutting or slitting cylinders, as viewed from the line 5—5, Fig. 1 looking in the direction of the arrow.

Fig. 6 is a section on the line 6—6, Fig. 5.

Fig. 7 is an enlarged detail sectional view of portions of the coöperating helical slitting knives and portions of the cylinders to which they are secured.

Fig. 8 is an enlarged detail view of the trimming mechanism.

Fig. 9 is a bottom plan view of the trimming knife or punch.

Fig. 10 is a top plan view of the trimming die.

Fig. 11 is an enlarged detail elevation of one of the winding boxes.

Fig. 12 is a section on the line 12—12, Fig. 11.

Fig. 13 is a detail view of the connection between one of the winding boxes and its feed screw.

Fig. 14 is a detail view of one of the winding cores, showing the attachment of a strip thereto.

In accordance with the process for which the machine herein shown is adapted, the paper or other web 26 (see particularly Fig. 3) is slit or cut diagonally, or at an inclination to its length, to form a plurality of strips 43, the cuts by which said strips are severed commencing at one edge of said web and terminating at the opposite edge thereof.

20 (Figs. 1, 2, and 5) denotes the machine frame, which is of suitable form and size to afford the necessary supports for the various machine parts hereinafter referred to.

21 denotes the main or power shaft of the machine which is journaled in suitable bearings in the frame 20 and is provided with a belt pulley 22 or other equivalent means whereby it may be rotated from any suitable source of power.

55 and 56 (Figs. 1, 2, 5, 6, and 7) denote upper and lower slitting cylinders carried by shafts 57 and 58 journaled in bearings 59 and 60 suitably mounted in the frame 20. The lower cylinder 56 is keyed to the shaft 58 upon which is secured a gear 62 meshing with a gear 64 on the power shaft 21.

Secured to the cylinder 56, as by bolts 68, is a gear 66 which meshes with a gear 67 keyed to the shaft 57. By these connections the shafts 57 and 58 are rotated in unison from the power shaft 21.

65 On the surfaces of the cylinders 55 and 56

are helical slitting knives 69 and 69^x respectively. The pitch of the helices followed by these knives upon the cylinders corresponds to the desired inclination of the strips 43 with respect to the web 26, the spacing of the convolutions of said helices accordingly corresponding to the width of said strips. The slitting knives 69 and 69^x are preferably formed in sections of suitable length secured to the cylinders by bolts or screws 70, (see Fig. 7) and ground when in place to produce perfect helices of substantially regular pitch. In order to provide a perfect cutting edge the meeting sides on the knives 69 and 69^x are preferably slightly undercut, as shown in Fig. 7.

In order to insure a close engagement between the coöperating slitting knives, thereby providing for a positive and efficient shearing action, the following construction is provided.

The upper slitting cylinder is not keyed to the shaft 57 but is loosely mounted thereon and is provided with an inwardly turned flange 71 formed with a series of openings 90 to receive pins 72 projecting inwardly from a ring 73 rotatably mounted within a cylindrical flange 74 on the gear 67 and held in place by means of a rib or retaining ring 75 suitably secured to the inner face of said flange 74. The ring 73 is formed with inwardly projecting lugs 76 between which and the lugs 77 on certain of the spokes of the gear 67 are interposed springs 78 whose tension is adjustable by means of screws 79 passing through the lugs 77. The rotation of the gear 67 is yieldingly transmitted through the springs 78, ring 73, and pins 72 to the cylinder 55. The arrangement of the parts is such that the tension of the springs 78 tends at all times to produce rotation of the cylinder 55 with respect to the cylinder 56 in a suitable direction to hold the coöperating edges of the helical knives 69 and 69^x in close engagement with one another. Moreover the connection between the cylinder 55 and rings 73 through the pins 72 is such as to permit said cylinder, by moving the same a slight distance longitudinally on the shaft 57, to be adjusted to different angular positions on said shaft (the pins 72 being engaged with different openings in the flange 71) while maintaining the same relative positions of the helices on the two cylinders, thereby causing the knives to engage one another at new points, so that should grooves or dents develop in the knives they could be so adjusted as to bring said grooves or dents at different relative points on the two knives.

The stock roll 23 (Figs. 1 and 2), upon which the web 26 and tympan sheet 24 are rolled together, is mounted in suitable bearings 25 at one end of the frame 20. The bearings 25 are preferably formed with open

- tops to permit a stock roll to be inserted or removed as may be required, said stock roll being retained in said bearings during the operation of the machine by latches 27.
- 5 The tympan sheet 24, after leaving the stock roll, preferably passes over an idler roll 28, journaled in suitable brackets on the machine frame, and is rewound upon a reel or roll 29 having a shaft 30 journaled in 10 open top bearings 31 similar to the bearings 25, and in which bearings said roll is retained by latches 32 similar to the latches 27. The shaft 30 is provided at one end with a pulley 33 (see Fig. 2) connected by 15 a belt 34 with a pulley 35 on the shaft 58 of the lower slitting cylinder, whereby the rewind roll 29 may be rotated to wind up the tympan sheet 24 as it is drawn from the stock roll 23. The belt 34 and pulleys 33 20 and 35 are merely illustrative of suitable driving means for the roll 29, it being obvious that said roll might be driven by the proper mechanical connections from any convenient moving part of the machine.
- 25 The web 26 is drawn from the stock roll 23 and fed to and past the slitting cylinders by means of feed rolls 36, of which two pairs are shown, one at either side of the slitting cylinders. Said feed rolls are 30 journaled in suitable bearings in the machine frame 20, the rolls of each pair being connected by gears 37 for rotation in unison. For driving the rolls 36, the lowermost gear 37 of each pair meshes with a 35 gear 38 which in turn meshes with the driving gear 62 of the lower slitting cylinder.
- As will be seen from Figs. 3 and 4, when the web 26 is cut to form strips 43, there 40 are formed, at the edge of said web, and at the ends of said strips, long tapering ends 39 which, for most purposes for which said strips are employed, are useless. Moreover, for some purposes it is desirable to give the ends of said strips 43 a special 45 shape, as, for example, that indicated at 40 in Fig. 4. For the purpose of trimming off the portions 39 and forming the ends 40, the following trimming mechanism is provided, said trimming mechanism being located beyond the slitting cylinders, and, as 50 herein shown, beyond the last pair of feed rolls 36.
- Secured to the frame 20 at suitable points adjacent the opposite sides thereof are 55 brackets 41 (see Fig. 2) having cylindrical portions 42 (see Figs. 1 and 8) constituting guides for plungers 44 having at their lower ends heads 45 (see Figs. 8 and 9) carrying trimming knives or punches 46. The cutting edges of said trimming knives or punches are formed by pieces of tool steel 60 properly ground and secured to the heads 45 by means of screws 47 having countersunk heads. The trimming knives or 65 punches 46 coöperate with trimming dies 48 (see Fig. 10) also composed of steel strips similar to those constituting the trimming knives and secured by screws to die blocks 49 carried by the machine frame 20. The form of the coöperating edges of the 70 punches or knives 46 and dies 48 corresponds to the desired form to be given to the ends of the strips 43, and as herein shown said knives and dies are of a shape to produce abruptly tapering ends, such as 75 are shown at 40 in Fig. 4.
- As above explained, the ends of the strips 43 to be trimmed are at the edges of the web 26, and the location of the trimming devices at opposite sides of the machine brings 80 them into the proper position to effect the desired trimming. Also, as above explained, each of the strips 43 has its opposite ends adjacent opposite sides of the web 26; what may be considered the forward end of the 85 strip being at one edge of said web, and what may be considered the rear end being at the opposite edge. Accordingly it will be understood that the two trimming devices have their trimming punches and dies 90 oppositely disposed, that shown at the bottom in Fig. 2 being so arranged as to form the end 40 shown at the right in Fig. 4, while that shown at the top in Fig. 2 is adapted to form the end 40 shown at the left 95 in Fig. 4.
- The downward movement of the plungers 44 to cause the knives to coöperate with the dies 48 in effecting the trimming operation is caused and controlled by the following 100 mechanism.
- 50 denotes a cam shaft suitably journaled in the machine frame and carrying at its end a gear 51 (see Fig. 1) connected by a gear 52 with the gear 62 on the shaft 58 of 105 the lower slitting cylinder, whereby said cam shaft is rotated. Mounted on the shaft 50 adjacent the sides of the frame are cams 53 having substantially circular peripheries provided at suitable points with notches 54. 110 Coöperating with the cams 53 are cam rollers 61 carried at the lower ends of rods 63 pivoted at their upper ends to levers 65. The rods 63 are guided for vertical movement in brackets or ears 80 and 81 formed on 115 and projecting from the die blocks 49 and plunger guide 42, respectively. Each of the levers 65 is pivoted intermediate its length to the upper end of the corresponding plunger 44, and, at its end opposite the rod 63, 120 to an arm 82 formed on and projecting from the plunger guide 42. It will be understood that the pivotal connections between the levers 65, on the one hand, and the plungers 44 and operating rods 63, on the other, are 125 such as to provide for sufficient play or looseness to permit the desired movements of the parts. 83 denotes springs within the plunger guides 42 and surrounding the plungers 44, said springs bearing at their lower 130

ends upon flanges or collars 84 on the plungers and at their upper ends upon caps 85 secured to the tops of said guides. The cams 53 acting through the rods 63 and levers 65, 5 normally hold the plungers 44 and trimming knives 46 in their elevated or inoperative positions, against the tension of the springs 83, as shown in Fig. 8. Periodically, however, as the ends 39 of the strips 43 are brought 10 into proper position beneath the trimming knives, the rollers 61 enter the notches 54, permitting the springs 83 to impart to the plungers 44 a quick downward movement to cause the knives 46 to trim the strips, said 15 plungers being quickly returned to normal position by the cams 53.

In order to locate the trimming devices in their proper positions within the edges of the web 26, while permitting the cam rods 20 63 to clear said edges, the levers 65 are arranged at an angle to the longitudinal axis of the machine, as shown most clearly in Fig. 2.

After passing the trimming mechanism 25 last described, the strips 43 are carried to the winding or reeling mechanism which, as herein shown, is as follows, reference being had to Figs. 1 and 2.

86 denotes a bevel gear mounted on the 30 shaft of the lower feed roll 36 of the last pair of feed rolls and meshing with a bevel gear 87 on a shaft 88 journaled in a suitable bracket projecting from the machine frame. The shaft 88 is connected by a flexible coupling 89 with a shaft 90 arranged longitudinally of the frame and journaled in suitable bearings thereon. Mounted on the shaft 90 are two series of bevel gears 91 and 92, respectively. The gears 91 mesh with bevel 35 gears 93 mounted on the shafts of horizontally disposed friction rolls 94 arranged transversely of the machine frame and journaled in suitable bearings thereon. The gears 92 mesh with bevel gears 96 on shafts 40 of feed screws 95 arranged parallel to the friction rolls 94 and also journaled in suitable bearings on the machine frame. Co-operating with the friction rolls 94 and feed screws 95 are winding boxes, designated as a 45 whole by the numeral 97, said winding boxes resting by gravity on the friction rolls 94, and having arms 98 provided at their ends with open threaded portions or half nuts 99 which rest by gravity on the feed screws 95. 50 (See Fig. 13.)

As shown in Figs. 11 and 12 each of the winding boxes 97 comprises end members 100 connected by a plate 101 between which and an open top receptacle 102 is clamped 55 the end of the arm 98. The end members 100 are provided with U-shaped slots 103 closed at the outer sides of the winding boxes by cover plates 104. 105 denotes weight or pressure rolls, having reduced 60 ends which enter the slots or grooves 103,

whereby said rolls are retained within the winding box, but are permitted free movement between the position shown in full lines in Fig. 12 and the position shown in dotted lines therein. 106 denotes the winding 70 core which (as shown in Fig. 14) preferably comprises a cylinder of wood or other suitable material substantially equal in length to the clearance between the end members 100 of the winding box, and which is provided with a diametric slot to receive the tapered ends 40 of the strips 43, whereby said strips may be initially secured to the cores. 75

By this construction the winding cores 106 80 are loosely disposed in the winding boxes, and are held in engagement with the friction rolls 94, so as to be rotated thereby, by the weight of the pressure rolls 105. Said pressure rolls are arranged in pairs, one pair 85 for each winding box, and the rolls of each pair occupy positions at opposite sides of and slightly above the corresponding winding core, thereby retaining said winding core in its box during the winding operation. As 90 the roll of fabric on a winding core increases in size the corresponding pressure rolls 105 move upwardly and outwardly, as indicated in dotted lines in Fig. 12, while remaining in contact with the fabric roll, 95 thereby not only preserving the necessary driving engagement between the latter roll and the friction roll 94, but causing the fabric to be wound with the proper degree of tightness. 100

The winding boxes rest wholly by gravity upon the friction rolls 94 and feed screws 95 and may be readily lifted therefrom or placed thereon in any desired position. When a winding box is thus placed in position on a friction roll and feed screw, said friction roll serves to rotate the winding core in said box to wind up a strip attached thereto, and simultaneously the feed screw serves to move the winding box gradually across 105 the machine as the winding progresses. 110

The receptacle 102 may conveniently be employed to hold empty cores, or, if found desirable, a weight or weights may be placed therein to assist in holding the winding 115 boxes firmly seated upon the friction rolls and feed screws.

As herein shown, for convenience in operation, two sets of friction rolls and feed screws are provided, although a less or 120 greater number may be employed, if preferred.

The complete operation of the machine is as follows: A roll of combined printed web and tympan sheet from the printing press 125 having been placed in position in the bearings 25, the end of the tympan sheet 24 is drawn off, passed over the idler roller 28, and secured in any suitable manner to the reel 29. The corresponding end of the web 130

26 is inserted between the first pair of feed rolls 36. The machine being started, rotation of the reel 29 serves to draw off and wind up the tympan sheet 24, while the web 26 is 5 fed past the slitting cylinders 55 and 56 and cut diagonally, as shown in Fig. 3, to form the strips 43. As the forward end of each strip passes under the trimming device at one side of the machine, and as the rear end 10 of said strip passes under the trimming devices at the opposite side of the machine, said trimming devices are operated, as heretofore explained, to trim off the waste portions 39 and shape the ends 40. As the end 40 of 15 each strip is thus shaped, the operator inserts the same into the slot in a winding core 106, places said winding core in a winding box 97, and deposits said winding box upon a convenient friction roll 94 and feed screw 20 95 at the proper side of the machine. Thereupon said core 106 is rotated to wind the strip thereon, and as the winding progresses the feed screw 95 causes the winding boxes to traverse the machine laterally, as required, 25 in order to compensate for the inclined position of the strips in the machine. It will, of course, be understood that, until the stock roll is exhausted, the machine operates continuously, so that, as the strips 43 (as cut 30 from the web 26) overlap one another transversely of the web, the winding of several strips will be in progress at the same time, although in different stages of completion. As the winding of each strip upon its core is 35 finished the transverse travel of the corresponding winding box will also be completed. The operator thereupon removes such winding box by lifting the same from its friction roll and feed screw, disposes of the completed roll of strip in any suitable manner, and returns the winding box to the other side of the machine for operation upon another strip whose winding is about to commence. 40

45 Having thus described my invention I claim and desire to secure by Letters Patent:

1. Slitting mechanism comprising a pair of cylinders provided with coöperating helical slitting knives, a driving element for one of said cylinders, and springs connecting said driving element and cylinder. 50
2. Slitting mechanism comprising a pair of cylinders provided with coöperating helical slitting knives, a ring connected to one of said cylinders, a gear, one or more springs connecting said gear and ring, a second gear carried by the other of said cylinders and meshing with said first-named gear, and 55 means for driving said last-named cylinder.
3. Slitting mechanism comprising a pair of cylinders provided with coöperating slitting knives, a ring connected to one of said cylinders and provided with lugs, a gear 60 provided with lugs, springs interposed be-

tween the lugs on said ring and gear, screws for adjusting the tension of said springs, a second gear carried by the other of said cylinders and meshing with said first-named gear, and means for driving said last-named cylinder. 70

4. Slitting mechanism comprising a pair of coöperating helical slitting knives of substantially regular pitch throughout their length, and means for supporting and operating said knives adapted to permit their relative angular and longitudinal adjustment to cause the same to engage each other in different relative positions. 75

5. Slitting mechanism comprising a pair of cylinders provided with coöperating helical slitting knives of substantially regular pitch throughout their length, shafts upon which said cylinders are mounted, driving connections intermediate said shaft, and means for yieldingly and adjustably connecting one of said cylinders with the corresponding shaft. 80

6. Slitting mechanism comprising a pair of cylinders provided with coöperating slitting knives, a shaft upon which one of said cylinders is rigidly mounted, a second shaft upon which the other of said cylinders is loosely mounted, a driving element adjustably connected with said last-named cylinder, intermeshing gears carried by said shafts, and springs connecting said driving element with the corresponding gear. 90

7. Slitting mechanism comprising a pair of cylinders provided with coöperating helical slitting knives, a shaft upon which one of said cylinders is rigidly mounted, a second shaft upon which the other of said cylinders is loosely mounted, intermeshing gears carried by said shaft, said last-named cylinder having an inturned flange provided with a series of openings, a ring having means adapted to engage said openings, and springs connecting said ring with the corresponding gear. 100

8. A machine of the character described comprising means for slitting a web diagonally into a plurality of strips and means located adjacent the edges of said web for trimming the tapered ends of the diagonal strips severed therefrom by said slitting means. 105

9. In a machine of the character described, the combination with a pair of coöperating helical slitting knives for slitting a web diagonally into a plurality of strips, and means for continuously driving said knives in unison, of a reciprocating trimming knife arranged beyond said slitting knives and adjacent the edges of said web, 115 and means for periodically operating said trimming knife to trim the tapered ends of said strips. 120

10. In a machine of the character described, the combination with means for 130

feeding a web longitudinally and for slitting the same diagonally into a plurality of strips, of means for winding said strips, and means interposed between said slitting means and winding means for trimming the ends of said strips.

11. In a machine of the character described, the combination with means for

slitting a web diagonally into a plurality of strips, of means for winding said strips, and means for moving said winding means transversely of said web during the winding operation.

In testimony whereof I affix my signature.

JOHN F. ANCONA.
